UNITED STATES PATENT OFFICE.

JOHN B. WOOD, OF MONTREAL, QUEBEC, CANADA.

ELECTRIC CIRCUIT.

SPECIFICATION forming part of Letters Patent No. 394,946, dated December 18, 1888.

Application filed May 21, 1887. Serial No. 238,947. (No model.)

To all whom it may concern:

Be it known that I, JOHN BAXTER WOOD, of the city of Montreal, in the district of Montreal and Province of Quebec, Canada, have 5 invented new and useful Improvements in Electric Circuits and Connections thereof; and I do hereby declare that the following is a full, clear, and exact description of the same.

10 This invention has reference to certain improvements in the circuits used in telephoning and telegraphing, by which, without the use of a central office, electrical connections may be made between any two of the stations 15 connected therewith—that is to say, in the same circuit—and disconnected at will without calling any other station or location than the one desired, which will enable a large number of instruments (each instrument be-

20 ing a location or station in a different location) to be attached upon the said circuit, and any one instrument at any station or location may be connected with any other instrument at any other station or location in 25 the same circuit at will.

The particular features which constitute the present invention will be hereinafter set forth, described, and claimed.

30 In the drawings hereunto annexed similar letters of reference indicate like parts.

Figure 1 shows a diagram of a construction of a circuit embodying my invention. Fig. 2 is a plan of a center second fly-back stop-watch mechanism. Fig. 3 is a diagram showing two of the stations or locations shown in Fig. 1. Fig. 4 is a diagram of a modification of the circuit shown in Fig. 1. Fig. 5 is a diagram showing a modification of the mechanism shown in Fig. 2, the section therein shown 35 being taken on line α , Fig. 6. Fig. 6 is a plan of the mechanism situated behind the front of the casing shown in Fig. 5. Figs. 7, 8, and 40 9 are details of construction.

Letter A is an ordinary metallic circuit running through any desired number of stations or locations in different situations which it is desired to connect together in circuit.

B is a closed circuit connected with battery C, also running through each station or location that the circuit A passes through, or, in other words, A and B form two circuits pass-

ing through a large or any desired number of stations or locations.

D is a "push-button," one of which will be provided at each station or location that is 55 connected with the circuit. By pressing the button D, I break the circuit B, as shown in Fig. 3; or as shown in Fig. 1, I break the circuits A and B and I connect one end of the circuit A with one end of the circuit B. The 60 other end of the circuit A is thereby connected with the ground-wire E, the other end of the circuit B being connected with the ground-wire F. Now, the current of battery C is thrown along the circuit, passing through the 65 magnets H H and G G, and thence on through all the stations or locations, returning to the battery, as shown in Figs. 1, 3, and 4, or else being grounded by wire E, as shown in Fig. 1. The opening and closing of the armatures 70 I and T by their respective magnets is thus caused to operate upon the knobs K and C' and causes the starting, stopping, and flying back to zero of the hand or connector N. Thus one pressure on the button D causes all 75 the armatures I in each of the stations or locations to press upon the knobs K in each station or location, (for it must be understood that each of the stations or locations connected in one circuit will be provided with the mechanism shown in station 1, Fig. 1, or stations 1 in 80 Figs. 3 and 4, with the exception of the batteries C and U, which will be provided at one station or location only,) and causes the hands or rotating connectors N to start. By a second pressure of the button D the hands or rotating connectors N will be all stopped, and by a third pressure of the button D the hands will all fly back to zero, in which position they are shown in the drawings. The manner in 85 90 which the said mechanism L accomplishes the above is the same as that in which the hand in an ordinary Swiss center second fly-back stop-watch is caused to do this, or as shown by the mechanism illustrated in Figs. 5 to 9, inclusively, which will be hereinafter explained. By pressing on the button V the heavy battery U is brought into circuit, operating the heavy resistance-magnets G G, attracting the armatures T, to which can be connected, as shown in Fig. 1, closed insulated points B' and open insulated points A' of the 95 100

circuit B. The closing of the armature T closes points A' and opens points B', thus cutting out the magnets H H while the magnets G G are in use, and causing them to press and operate the knobs C', which at all times causes the flying back to zero of all the hands or rotating connectors N. But this said heavy battery is not an absolute necessity. I only provide it for greater convenience. Around the 10 circumference of the dial b² of the said watch mechanism L is placed a sufficient quantity of numbers, to give a separate number to each station or location that is connected in the circuit, and as the hands or rotating connectors 15 N, which I use as a direct electrical connector, reach the number on the dials of the mechanisms L which represents the station or location desired to be communicated with, the second pressure on the button D is given. This 20 causes a second pressure of the armatures I on the knobs K, whereby all the hands or rotating connectors N are stopped and raised to form a connection with the insulated point a² upon the end of a wire, O, over the mechanism L (or in front of it, as the case may be) 25 in the station or location desired, as will be hereinafter more particularly described, making a direct connection in the said desired station or location through the line O to the ground P with a signal or call-bell, Y, or other 30 electrical instrument that may be placed thereon. When this is arranged as shown in Figs. 3 and 4, the bell Y will ring until the telephone Q is taken off its hook R; or, if arranged as shown in Fig. 1, the call or bell will 35 ring as long as the second pressure on the button D is continued; or, in other words, the said call can be arranged in any manner well known to electricians and as at present in ordinary use.

As shown in the drawings, there are in circuit six stations or locations; consequently there are six numbers on the dials b² in each station or location; and at the number on the 45 dial b² which represents the number of the station or location there is situated in each station or location an insulated point, a². This will be understood by Figs. 3 and 4, where in station 1 the insulated point a² is at 50 1 on the dial b², and at station 2 the said insulated point is at 2 on the said dial, and so on it will be arranged for each of the stations or locations.

Q is an ordinary telephone-trumpet, the 55 taking off of which from the hook R opens the flexible points S and closes the flexible points S'. In Figs. 3 and 4 the circuit B passes through the flexible contact-points S, the closing of points S' causing its current of 60 electricity to pass through the transmitter Y' and induction-coil Y², or by taking off the telephone Q at the stations or locations calling and called a direct connection for speaking purposes is made upon the wire A, as shown in Fig. 3, or upon the wire B in Fig. 4. When the circuits are arranged as shown in 65 Figs. 1 and 3, each of the stations or locations

is provided with a button, D, magnets G G and H H, armatures I and T, also the mechanism L, call-bell Y, and telephone; but when 70 the circuit is arranged as shown in Fig. 4 the magnets G G and armatures T are dispensed with.

In one station or location only it is necessary to place, in addition to the above, the 75 batteries C and U and button V. These may be placed in any one station or location of the circuits that is desired; yet, if it is so desired, a battery may be placed in each station or location, such being done in a similar way as 80 in ordinary use at present.

In speaking of stations or locations I wish it to be understood that the same may be either close together or many miles distant from each other, just as desired. 85

Battery U is a heavy battery, which need only be used should the hands or rotating connectors N in the various mechanisms L at the several stations or locations connected with the circuits A and B become disarranged 90 with regard to having all of them properly returned to zero, should for any reason they fail to do so. By pressing on the button V, I open circuit A, as shown in Fig. 1, or circuit B, as shown in Fig. 3, thus throwing the 95 said battery into circuit and causing the armatures T to be operated by the magnets G G and operate the knobs C', the effect of which will be hereinafter described.

Although, as shown in Figs. 1 and 3 and 100 the description hereinabove relating thereto, two circuits, A and B, are used, yet, as shown in Fig. 4, but one circuit, B, need be employed. This is done in the following manner: The circuit B is opened and the ends of it attached 105 to each end of the battery C. I open the circuit at about the position of the button D, the opening and closing of the circuit at that point attracting and releasing armatures I through the magnets H H, the closing of the 110 circuits causing the armatures I to press the knobs K, and thereby operating the mechanisms L, as hereinafter described.

The mechanism L, *per se*, which I am about to describe, and as shown in Figs. 2, 5, 6, 7, 115 8, and 9, forms no part of the present invention, (being the subject-matter of an application filed in the Patent Office in the names of P. W. Wood and myself, Serial No. 242,003, June 21, A. D. 1887,) only in so far 120 as it contains a rotating hand or electrical connector N, which is started, stopped, and in being stopped is elevated or moved forward, and thus makes a good connection between the wires M and O, as shown in Figs. 1 and 5, 125 and after the connection between the wires M and O is no longer required it is caused to fly back to zero, where it remains while not in use.

Before describing the mechanism shown in 130 Figs. 5 to 9, inclusively, I wish to make the following general remarks: A center second fly-back stop-watch is, as I might say, in a watch an independent movement or mechan-

ism from the time-keeping mechanism, (in many cases being driven by an independent mainspring,) which stands at rest with its hand at zero, and is used chiefly for racing purposes, so as to get the exact starting-time, finish, and intervening time. In stopping, it is placed out of contact with the time-keeping mechanism. It contains a rotating hand which may be started, stopped, and ⁵ turned to zero at a bound, and as the hand in stopping is raised to a higher level or thrown to a more forward position than that at which it is rotated, the said hand can be made to ¹⁰ press against the insulated ends of the wires ¹⁵ M and O, as shown in Fig. 5, and made to form a good connection for currents of electricity; and as a watch mechanism is one that contains a very light action it can be operated by a very light current of electricity, thus ²⁰ being specially useful for such purposes; also, as the rotating wheel (hereinafter described) will only be geared or thrown into friction and motion at the longest time for not more than thirty or sixty seconds, no ²⁵ perceptible variation in the time of its rotation can occur between the number of movements in a circuit of stations or locations. As a single knob or push-point alone is necessary to accomplish all three motions—viz., starting, ³⁰ stopping, and flying back to zero—but one battery alone need be used, which I also use for the further purpose of signaling upon a call-bell, which is placed out of circuit and is only brought into circuit through the hand or ³⁵ rotating connector when it is stopped and brought to bear against its insulated point in its own station or location, and on the taking off of the telephone-trumpet from its hook the same battery can be made use of for the ⁴⁰ telephone-transmitter. As the hand can be started and stopped without stopping any of the watch or time-keeping movement, the liability of the watch not starting again is done away with, and this there is great danger of ⁴⁵ at all times if the time-keeping movement or watch mechanism is stopped, particularly when the mainspring is partly or nearly run down.

The mechanism shown in Figs. 5 to 9, ⁵⁰ inclusively, may be shortly described as follows: ⁵⁵ a^5 is an ordinary casing. In the upper space b^5 is situated a watch or other mechanism. (Not shown because it only bears the same relation to the mechanism that a steam-engine or other motor does to the mechanism it is arranged to give motion to.) If the motor is a watch mechanism, then of such mechanism b^3 is the ordinary minute gear-wheel and axle, a^3 , journaled in the casing a^5 in an ordinary manner; or, if other motors are used, then b^3 is a wheel, and a^3 an axle arranged to revolve continuously at the speed of about one or two revolutions per minute. On the axle a^3 is secured a knife-edged toothed gear-wheel c^3 . ⁶⁰

e^3 is an axle provided with a knife-edge gear-wheel d^3 . This wheel d^3 and axle e^3 are

situated so that when the wheel d^3 is moved to the position of line y^3 in Fig. 5 it intermeshes with the wheel c^3 and is revolved ⁷⁰ thereby. The axle e^3 extends through the casing a^5 at points f^3 , and has secured upon it a flanged collet, h^3 , and an ordinary heart-shaped cam, m^3 . (See Figs. 5 and 9.)

b^3 is a head provided with a knife-edge to ⁷⁵ press upon the periphery of the cam m^3 .

i^3 is a spring, to the upper end of which is attached the said head b^3 , the lower end of the spring i^3 being secured to casing a^5 or any suitable projection thereof. ⁸⁰

On the part of the axle e^3 which extends through the front of the casing a^5 is secured a hand or rotating connector, N , provided with electric point a^6 . On the said hand is formed a projection, a^7 , which, as shown, appears to form a continuation of the said axle e^3 , but which is an electrical point. ⁸⁵

g^3 is a spring-bar, one end of which is entered between the flanges of the collet h^3 , and the other end is gripped in a rest, b^6 , which ⁹⁰ holds it rigidly from any longitudinal and transverse motion, while by its flexibility it is enabled to move freely backward and forward or up and down, as the case may be.

b^7 is an axle on which is secured a double ⁹⁵ wheel or two wheels, b^8 and b^9 . The axle and wheels are situated so that a portion of the wheel b^8 will come immediately at the back or under the spring-bar g^3 . The edge of the wheel b^8 is cut in the form of teeth of equal ¹⁰⁰ length in a similar manner that a verge watch-wheel is cut; but in the present case these teeth are of unequal height. They are cut in sets of three teeth, marked 1, 2, and 3. (See Figs. 5 and 7.) The bottoms of all the teeth ¹⁰⁵ 1 are at an equal height with one another; so, also, are the bottoms of those marked 2 and 3.

The spring-bar g^3 is provided with a pawl, c^5 , attached securely thereon or made integral ¹¹⁰ therewith. The point of this pawl is arranged to rest in the bottom of the teeth 1, 2, and 3, as shown in Fig. 5. It is resting at the bottom of one of the teeth 1. If the wheel b^8 is turned round in the direction of the arrow in Fig. 7 ¹¹⁵ the amount of one tooth, it will cause the spring-bar g^3 to rise to the position of line x' , Fig. 5, and move the axle e^3 and wheel d^3 to the line y^3 , in which position it will intermesh with the wheel c^3 and be rotated thereby; also ¹²⁰ the hand N . If the wheel b^8 is again moved round the amount of one tooth, it will bring the point of the pawl to rest at the bottom of one of the teeth 3, which, being at a greater height, will move the spring-bar g^3 to the position shown by the dotted line x^2 . This moves the wheel d^3 to the position in front, above, or "beyond," out of contact with the wheel c^3 , as shown by the position indicated in front of the line y^3 in dotted lines in Fig. ¹²⁵ 5, and in this position it is no longer rotated by the wheel c^3 .

s^3 is a knife-edged stop situated on the casing a^5 , so that just as the wheel d^3 is moved

forward beyond contact with the wheel c^3 it is caught and retained in the position it has been rotated to by the wheel c^3 . By moving the wheel b^8 the amount of another tooth the pawl c^5 is again brought to the bottom of one of the teeth 1, which causes the wheel d^3 and axle e^3 to be again lowered to the position shown in solid lines in Fig. 5, whereupon by the action of the spring i^3 pressing the head b^3 upon the periphery of the cam m^3 the hand N is caused to fly back to zero.

I will now describe how the wheels b^8 and b^9 are to be operated to actuate the spring-bar g^3 , and thus cause the above-described results.

15 E^4 is a spring-bar attached to knob K , provided with a pawl, F^4 , arranged to engage with the teeth 1, 2, and 3 of the wheel b^8 . This is carried in a guide, G^4 , attached and suitably situated on the back of the casing a^5 . The 20 bar E^4 is provided with two collars or other stops, H^4 , so arranged that they will allow the bar E^4 to move longitudinally the amount required for the pawl F^4 to revolve the wheel b^8 the amount of one of the teeth 1, 2, or 3, as 25 the case may be. A spring, I^4 , may be provided, as shown, to return the spring-bar E^4 to the position shown in Fig. 7, ready for the next operation of the magnets H H upon the armature I ; or the bar E^4 is attached to the 30 armature. Any motion of the wheel b^8 in a reverse direction which would be caused by the return of the spring-bar E^4 is prevented by the pawl c^5 of the spring-bar g^3 .

I would here remark that the magnets H H 35 are made of as light resistance as possible.

With regard to the wheel b^9 and the means by which it is operated, K^4 is a spring-bar provided with a pawl, L^4 , to act on the teeth o^4 of the wheel b^9 . This bar is carried in a 40 guide, G , and is provided with stops H^4 and a spring, I^4 , if desired, exactly similar to those of the bar E^4 , and is operated in the same way by the magnets G G (which are heavy resistance) and armature T that the spring-bar E^4 45 is by the magnets H H and armature I .

It has been hereinbefore mentioned that for each set of teeth in the wheel b^8 there is one tooth on the wheel b^9 , and for the purpose of giving the three described positions 50 to the wheel d^3 there are three teeth in each set of teeth, of three different heights, the teeth on the wheel b^9 being so arranged that each time the pawl F^4 comes to the bottom

of one of the teeth 1 on the wheel b^8 the pawl L^4 will come to the bottom of a tooth o^4 55 on the wheel b^9 . Now should, for any reason, the mechanisms in the various stations or locations in a circuit have become deranged, so that the hands N do not all properly stand at zero, it is only necessary to send a current of 60 electricity through the magnets G G , which, by the armature T , spring-bar K^4 , and pawl L^4 , turns the wheel b^9 the amount of one of the teeth o^4 , and thus brings simultaneously all the hands or rotating connectors N to zero. 65

What I claim, and wish to secure by Letters Patent, is as follows:

1. The combination, with a circuit for telephonic, telegraphic, or electrical purposes, of a connector at each station, comprising a dial 70 with a contact-point connected to a ground branch including a signal-instrument, said contact-point having a different circumferential position from that at the dial of any other station, and a hand or pointer rotated at will 75 by the center second fly-back stop mechanism at a different level from that at which it is stopped, substantially as described.

2. In a station call apparatus, a dial having a connection for a signal branch and a rotatable hand to make connection therewith, in combination with the stepped ratchet and operating mechanism of the fly-back stop mechanism, substantially as described. 80

3. A telephone-station apparatus consisting 85 of the fly-back rotatable hand for connecting the line to the signal-bell branch, a telephone transmitter, receiver, and induction-coil, the switch-hook for making and breaking the telephone and signal circuits, and an operating- 90 battery and push-button in the circuit, in combination, as described.

4. In combination, a telephone-call apparatus consisting of a rotating connector, a transmitter, a receiver, and hook, and an induction- 95 coil, in connection with a closed circuit and a metallic circuit extending through a number of stations or locations of such telephones, and magnets G , with the battery of said closed circuit placed in any one of said stations or 100 locations and arranged to actuate any or all of the said stations or locations, as described.

JOHN B. WOOD.
